UNITED STATES PATENT OFFICE.

CHARLES KRETSCHMER, OF PUEBLO, COLORADO.

WAGON-STANDARD.

SPECIFICATION forming part of Letters Patent No. 636,814, dated November 14, 1899.

Application filed June 12, 1899. Serial No. 720,224. (No model.)

To all whom it may concern:

Be it known that I, CHARLES KRETSCHMER, a citizen of the United States, residing at Pueblo, in the county of Pueblo and State of Colorado, have invented a new and useful Wagon-Standard, of which the following is a specification.

My invention relates to certain improvements in wagon-standards and aims to provide a standard which will permit adjustment of a stake to the requirements of the load on the wagon and which may be firmly secured to the bolster without splitting of the same. These objects I attain by the use of the construction illustrated in the annexed drawings; and the invention consists in certain novel features of the same, as will be hereinafter first fully described and then particularly pointed out in the claims.

In the drawings referred to and forming a part hereof, Figure 1 is a perspective view of a standard constructed in accordance with my invention. Fig. 2 is a vertical section of the same, taken longitudinally through the bolster. Fig. 3 is a detail perspective view looking at the under side of the lower end of the standard.

The bolster A is of the usual form and size. In carrying out my invention I secure upon the upper side of the bolster a metal plate B, the edges of which follow the edge of the bolster, and within a narrow groove C in the bottom of the bolster I secure a strip of metal D. Near its end the upper plate B is provided with a perforation E, which registers with a socket F in the upper side of the bolster, as shown more clearly in Fig. 2. The standard consists of a base-plate G and plates or walls H, rising therefrom. The base-plate is provided with the depending rib or flange I, which follows the contour of the bolster and fits against and around the end of the same. An opening J is formed in the plate near its outer end, through which a bolt K may be passed downward through the bolster and secured by a nut L, turned home against the strip D. At the inner corners of the base-plate are provided lateral enlargements M, which serve as bearings for the bolts N, which are inserted downward through the same and extend below the bolster on opposite sides of the same. Upon the lower ends of these bolts

I mount a clip-plate O, which is adapted to bear against the bottom of the bolster, and below the said plate the securing-nuts P are mounted on the bolts. When the nuts are turned home, the clip-plate is forced against the bolster and the several parts secured, as will be readily understood. In order to facilitate the placing of the standard in the proper position on the bolster, I provide at the center of the inner edge of the base-plate a teat Q, which is adapted to enter the opening E and engage the socket F. The vertical plates or walls of the standard constitute an open box adapted to receive a stake R. Across the open outer side of the box and connecting the side walls are a plurality of braces S, which serve as bearings for set-screws T, adapted to be turned home against the stake to hold the same within the box, and in order to provide a firm hold for the set-screws and prevent wear on the stake I face the stake with a metal reinforcing-strip U, as shown.

It will be seen at once that I have provided a standard which is light and at the same time very strong. The teat and depending flange or rib on the base-plate enable the user to instantly set it in proper position on the bolster and also aid in maintaining it in that position. The device is firmly secured in place by simply turning home three nuts. The vertical walls of the standard are of the proper height to hold an ordinary load. Should the load on the wagon, however, rise to a height greater than the said walls, the stake R is raised to the height necessary to hold the load and is held at that height by turning the set-screws home. It will thus be seen that the standards and stakes together form an extensible or adjustable standard which can be instantly adjusted to the requirements of any particular load.

From the foregoing it is thought that the construction, operation, and the many advantages of the herein-described wagon-standard will be apparent to those skilled in the art without further description, and it will be understood that changes in the size, shape, proportion, and minor details of construction may be resorted to without departing from the spirit or sacrificing any of the advantages of the invention.

Having thus described my invention, what I claim, and desire to secure by Letters Patent, is—

1. The combination with a standard in the form of an open box, of a stake slidingly mounted therein, a metal strip extending lengthwise of opposite sides of said stake and bent around one end thereof, and a set-screw mounted in the box and bearing against the metal strip on the stake, substantially as set forth.
2. The combination of the bolster having a socket in its upper side, a standard having its base-plate provided with a seat adapted to engage said socket, and with a depending flange or rib to fit around the end of the bolster, said flange or rib having thickened and vertically-apertured ends, and fasteners passing through said apertured ends at opposite sides of the bolster, substantially as set forth.
3. The combination of the bolster having a socket in its upper side and longitudinal groove in its under side, of a metal plate secured on the upper side of the bolster and

provided with an opening registering with 25 the socket in the bolster, a metal strip secured in the groove in the under side of the bolster, a standard having its base-plate provided with a depending flange or rib fitting around the end of the bolster, and with a seat engaging the socket and the opening registering therewith, a bolt inserted through the base-plate of the standard and the metal plate and strip on the bolster, a nut on the lower end of said bolt turning home against the metal 30 strip, bolts inserted through the rib of the base-plate and passing below the bolster on opposite sides of the same, a clip-plate mounted on the lower ends of the said bolts, and fastening-nuts adapted to be turned home against 40 the said clip-plate, substantially as set forth.

In testimony that I claim the foregoing as my own I have hereto affixed my signature in the presence of two witnesses.

CHARLES KRETSCHMER.
